UNITED STATES PATENT OFFICE.

MORRIS ROTSTEIN AND ROBERT NICHOLSON, OF VICKSBURG, MISSISSIPPI.

KNOCKDOWN CAMP STOVE.

Application filed February 28, 1927. Serial No. 171,621.

The invention aims to provide a new and improved form of knock-down camp stove of sectional construction, this construction being such that an upper, oven-and-flue-containing wall and a top secured thereto, may be disposed within a lower, fire-retaining wall when the stove is disassembled.

With the foregoing in view, the invention resides in the novel subject matter herein-
10 after described and claimed, the description being supplemented by the accompanying drawing.

Fig. 1 is a front elevation of the stove set up for use.

15 Fig. 2 is a vertical sectional view on line 2—2 of Fig. 1.

Figs. 3 and 4 are horizontal sections on the correspondingly numbered lines of Fig. 2.

20 Fig. 5 is a vertical transverse section on line 5—5 of Fig. 2.

Fig. 6 is a vertical sectional view showing the sections of the stove disassembled.

25 Fig. 7 is a vertical section illustrating the manner in which the sections of the stove are engaged with each other when they are to be carried from one place to another.

The form of construction selected for illustration in the present application, will 30 be rather specifically described, with the understanding however, that within the scope of the invention as claimed, variations may be made.

In the drawings above briefly described, 35 the numeral 8 designates a bottom which supports the fire when the stove is in use, said bottom preferably having detachable legs 9. At its periphery, this bottom is provided with an upwardly projecting continuous flange 10, which is spaced inwardly to some extent from its peripheral edge. Resting upon this peripheral edge portion of the bottom 8 and fitting removably around the flange 10, is a lower wall 11 which retains 40 the fire when the device is in use, said wall being provided with a fuel-feeding and draught-controlling door 12 which is hingedly supported at 13 and held closed by a suitable spring catch or the like 14. The upper end of this wall 11 is contracted as indicated at 15, and a downwardly facing, beveled, internal shoulder 15^a is formed at the lower portion of the reduced end, while a similar but upwardly facing shoulder 15^b 45 is also provided, externally.

Removably fitting around the contracted upper end 15 of the lower wall 11, and resting on shoulder 15^b, is an upper, continuous, oven-and-flue-containing wall 16, this upper wall being of less height and of less diameter than the wall 11 so that it may be received within the latter when the parts are to be nested for carriage from one place to another or for storage, as will be clear from Fig. 7. The oven 17 and the smoke flue 18 within the confines of the wall 16, are practically identical with the oven and flue of our U. S. Patent No. 1,464,271 and hence need not be described in detail. It may be mentioned however, that the hinged oven door 19 is held normally closed by a spring catch 20 (Fig. 4), is provided with an external handle 21, by means of which it may be opened, and is formed with a recess 22 into which this handle is swung when the wall 16 is to be nested within the wall 11. Attention may also be invited to the fact that we prefer to provide the interior of the oven with opposed apertured lugs 23 with which the downturned ends 24 of rods 25 may be engaged, providing a grating upon which to rest baking pans or the like.

A top 26 is secured upon the upper end of the wall 16 and is preferably provided with a downwardly projecting continuous flange 27 which surrounds said wall, said top 26 being also provided with a smoke outlet 28.

When the stove is to be carried from one place to another, the sections 8, 11 and 16 are disconnected as in Fig. 6, and the legs 9 are removed. Then, the legs are placed in the oven 17, the section 16 is inserted into the section 11 and the bottom section 8 is again applied to the section 11. Thus, a compact nested structure is produced which may readily be carried in small space, for instance in an automobile. Attention is invited to the fact that when the parts are nested, as seen in Fig. 7, the top 26 abuts the shoulder 15^a holding the section 16 against 50 the shoulder 15^b holding the section 16 against 100 the section 11. The legs 9 and rods 25 may be wrapped to prevent rattling if desired.

When the stove has reached the point at which it is to be used, it may be quickly and 105 easily assembled, and used to advantage.

It will be observed from the foregoing that a simple, inexpensive and desirable construction has been provided and that this construction may be readily set up for use 110

or condensed for carrying or storage, as occasion may demand. Hence, the stove is well adapted for camping purposes, but is not restricted to this particular field of use.

3. We claim:

1. A knock-down stove comprising a fire-supporting bottom, a fire-retaining wall removably connected with said bottom, an oven-and-flue-containing wall removably connected with the upper end of said fire retaining wall, said oven-and-flue-containing wall being of less diameter than said fire-retaining wall and being receivable within the latter when the stove is disassembled, and a top secured to the upper end of the oven-and-flue-containing wall and also receivable within said fire-retaining wall; the aforesaid bottom being re-applicable to the lower end of the fire-retaining wall after insertion of the other wall and the top therein.
2. A structure as specified in claim 1; the upper end of said fire-retaining wall being reduced, providing an internal downwardly facing shoulder and an external upwardly facing shoulder, the external shoulder limiting downward sliding of the oven-and-flue-retaining wall when the stove is set up for use, the internal shoulder abutting said top and holding the same and said oven-and-flue-retaining wall against upward movement

when these parts are within the fire-retaining wall.

3. A knock-down stove comprising a fire-supporting bottom having an upstanding annular flange; a continuous fire-retaining wall removably telescoped with said flange, said wall being contracted at its upper end providing a downwardly facing internal shoulder; an oven-and-flue-containing continuous wall having its lower end removably telescoped with said contracted upper end of the fire-retaining wall, said oven-and-flue-containing wall being of less height than the fire-retaining wall, and a top having a smoke outlet and a continuous downwardly projecting flange, the latter being telescoped with and secured to the upper end of said oven-and-flue-containing wall; the oven-and-flue-containing wall and top being receivable within the fire-retaining wall when the stove is disassembled, said top then abutting said shoulder, said bottom being re-engageable with the lower end of said fire-retaining wall to hold the nested parts in nested relation with each other.

In testimony whereof we have hereunto affixed our signatures.

ROBERT NICHOLSON.
MORRIS ROTSTEIN.
